[57] CLAIM

The ornamental design for a combined pendant and opener for a split ring key holder, as shown and described.

DESCRIPTION

FIG. 1 is a top plan view of a combined pendant and opener for a split ring key holder showing my new design;
FIG. 2 is a right side view;
FIG. 3 is a left side view;
FIG. 4 is a front elevation view; and,
FIG. 5 is a perspective view shown in a position of use, the
broken line showing of a key ring is for illustrative purposes
only and forms no part of the claimed design.
